UNITED STATES PATENT OFFICE

143,998

DESIGN FOR A WEATHER OBSERVATION BALLOON RADAR CORNER REFLECTOR TARGET

Kenneth E. Shreeve and George M. Pro,
Kansas City, Mo.

Application June 18, 1945, Serial No. 120,178

Term of patent 7 years

(Cl. D71—1)

To all whom it may concern:

Be it known that we, Kenneth E. Shreeve and George M. Pro, citizens of the United States, both residing at Kansas City, county of Jackson, and State of Missouri, have invented a new, original, and ornamental Design for a Weather Observation Balloon Radar Corner Reflector Target, of which the following is a specification, reference being had to the accompanying drawing, forming a part thereof.

Figure 1 is a perspective view of the weather observation balloon radar corner reflector target showing our new design, and

Figure 2 is an inverted plan view thereof.

We claim:

The ornamental design for a weather observation balloon radar corner reflector target, as shown.

KENNETH E. SHREEVE.
GEORGE M. PRO.
